(57) **CLAIM**

The ornamental design for a liquid dispenser, as shown and described herein.

DESCRIPTION

FIG. 1 is a perspective view of a liquid dispenser, showing my new design;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom view thereof; and,

FIG. 8 is the perspective view thereof, in which the liquid dispenser is positioned over a dishwasher air gap in order to illustrate a sample environment.

The broken lines in the figures show portions of the liquid dispenser which form no part of the claimed design.

The broken lines in FIG. 8 depict an environmental dishwasher air gap and a counter that forms no part of the claimed design.

The dot-dash lines represent the boundaries of the claim and form no part thereof.
